CUTTER CHAIN

Edward J. Doberstein, Blue Island, Ill., assignor to Goodman Manufacturing Company, Chicago, Ill., a corporation of Illinois

Application December 15, 1941, Serial No. 422,958

6 Claims. (Cl. 262—33)

This invention relates to improvements in cutter chains for kerf-cutting machines.

The principal objects of my present invention are to provide a new and improved form of cutter chain having a readily renewable bit holding member, which entirely surrounds and protects the bit holding portion of the cutter chain against abrasive wear.

Another object of my invention is to provide a new and improved form of cutter chain and drive sprocket therefor, so arranged that each link of the chain is engaged by a tooth of the sprocket, to prevent buckling of the chain and to increase the life thereof.

A more specific object of my invention is to provide a new and improved cutter chain and drive sprocket therefor, which is so arranged as to have center teeth engageable with the ends of the connecting links of the chain between the sides of the yokes of the bit carrying links of the chain and to have alternate teeth spaced from said center teeth for engagement with the outer sides of the yokes of the chain, to render it unnecessary to cut away the connecting links of the chain to provide bit receiving portions therein, and thus to provide a stronger more durable chain than formerly.

A still further object of my invention is to provide a new and improved connecting means of a simplified construction, for connecting the links of a cutter chain together, so arranged that the chain may readily be detachable and the connecting means may be held from pivotal movement with respect to the chain.

Other objects of my invention will appear from time to time as the following specification proceeds and with reference to the accompanying drawings wherein:

Figure 1 is a plan view of a cutter chain constructed in accordance with my invention, showing the cutter chain trained around its drive sprocket;

Figure 2 is a sectional view taken substantially along line 2—2 of Figure 1;

Figure 3 is an enlarged detail plan view of the cutter chain shown in Figure 1, with certain parts broken away and certain other parts shown in horizontal section;

Figure 4 is a fragmentary plan view drawn to the same scale as Figure 3, but showing the bit holding means in a released position;

Figure 5 is a sectional view taken substantially along line 5—5 of Figure 3;

Figure 6 is a sectional view taken substantially along line 6—6 of Figure 3;

Figure 7 is a sectional view taken substantially along line 7—7 of Figure 3; and

Figure 8 is a sectional view taken substantially along line 8—8 of Figure 3.

In the drawings the cutter chain is shown as trained around a drive sprocket 10 on a vertical drive shaft 11, and comprises a plurality of bit carrying links 12, 12 having cutter bits 13, 13 mounted therein, with a plurality of connecting links 14, 14 connecting said bit carrying links together. Each of said bit carrying links is of a well known yoke construction having a pair of parallel spaced legs 15, 15 embracing eyes 16, 16 at opposite ends of said connecting links. The ends of the legs of the yokes of said bit carrying links are of a curved formation, to conform to the form of the teeth of the cutter chain drive sprocket, and are adapted to be engaged by alternate upper and lower teeth 17, 17 of said sprocket, extending along opposite sides of said connecting links. The ends of the eyes of the connecting links of the chain are likewise of a curved form, conforming to the form of the teeth of the cutter chain sprocket and, as herein shown, are adapted to be engaged by center teeth 18 of the sprocket arranged alternately with said upper and lower teeth and to extend between the legs of the yokes of the bit carrying links of the chain, so that each link of the cutter chain is engaged by a sprocket tooth. This provides a more uniform drive to the chain than formerly and prevents buckling thereof and reduces wear on the pins and bearing members connecting the links of the chain together. This improved construction also renders it unnecessary to cut away the connecting links of the chain to form tooth receiving sockets therein, as has heretofore been done.

The connecting links and yokes of the chain are pivotally connected together by means of bushings 21, 21 mounted on hollow pins 22, 22. Said bushings extend within the eyes of the connecting links of the chain, and said hollow pins extend through said bushings and through the legs 15, 15 of the yokes of the chain. Each of said hollow pins is provided with an irregular head 23 adapted to have engagement with an elongated recessed portion 20 formed in one leg 15 of the yoke of the bit carrying link of the chain. A pin 24 extends through said hollow pin and is adapted to hold said hollow pin in position in the legs 15, 15. Said pin has an irregular head 25 adapted to fit in an elongated shouldered portion 20 of the leg of the yoke opposite 55 from the head 23. The end of said pin opposite

from said head is adapted to be riveted to said hollow pin, to hold said hollow pin to the legs of the yoke. Said irregular heads of said pins and said hollow pins, engaging said elongated shouldered portions, thus prevent turning movement of said pins and rivets with respect to each other and to the yoke of the chain and provide readily detachable mountings for the bushings 21, 21.

Referring now in particular to the novel means for holding the cutter bits 13, 13 in the bit receiving links of the chain, a bit receiving portion 27 projects from a bridge 29, connecting the legs of the yoke of the chain together. Said bit receiving portion is provided with a plane forward surface 30, inclined inwardly and rearwardly from the outer end of said bit receiving portion, against which the rear face of the bit is adapted to abut and be held in a forwardly inclined position. Said bit receiving portion is likewise provided with an inclined surface 31 inclined in an upward and forward direction from the bottom of said plane surface at the angle of inclination of the lower cutting edge of the bit, and adapted to form a support and stop for the bit. A tongue 33 is spaced upwardly from the bridge 29 and projects forwardly from said bit receiving portion and has slidable engagement with a notch 34, formed on an inside of a forward wall of a bit holding shield 35. Said bit holding shield is adapted to extend over and surround said bit receiving portion and has an apertured top portion which is indicated by reference character 36, which forms a passage for the bit 13 and has slidable guiding engagement with an integrally formed outwardly projecting guiding portion 37 of said bit receiving portion. An inner face 39 of said bit holding shield is inclined to conform to the angle of inclination of the bit and the plane surface 30, and is adapted to engage the forward face of the bit, to clamp said bit in position.

The means for moving said bit holding shield into clamping engagement with the bit, as herein shown, includes a screw 49 threaded within a rear wall 41 of said bit holding shield and having a plain inner end 42 engaging a recess formed in the rear part of the bit receiving portion 27, so that rotation of said screw in a clockwise direction will draw said shield in a direction to engage the surface 39 with the forward face of the bit and will clamp the bit in position in said bit receiving portion. When said screw is loosened a distance sufficient to permit the tongue 33 to come out of engagement of the notch 34 and to permit the end 42 of said screw to come out of engagement with the apertured portion of the bit receiving portion 27, and bit holding shield may readily be removed and renewed. It should be understood, however, that said shield is not renewed when changing bits, but is only renewed when worn.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

I claim as my invention:

1. In a cutter chain, a plurality of alternately arranged bit carrying and connecting links, said bit carrying links each having a projecting bit carrying portion, and means for holding a bit

in said bit carrying portion and for protecting said bit carrying portion during the cutting operation including a shield adapted to extend around said bit carrying portion and having a surface adapted to engage an advance side of a bit and also having an apertured portion through which the bit extends, and a screw threaded in a rear portion of said shield and engaging a rear portion of said bit carrying portion, for drawing said shield rearwardly along said bit carrying portion and for engaging said engaging surface of said shield with the advance side of said bit.

2. In a cutter chain, a plurality of alternately arranged bit carrying and connecting links, each of said bit carrying links having a projecting bit carrying portion having a bit receiving recess formed therein, and renewable means for protecting said bit carrying portion against abrasion and for holding a cutter bit in said bit carrying portion including a shield having interengaging longitudinally slidable connection with said projecting bit carrying portion to prevent movement of said shield outwardly away from said bit carrying portion when in position to clamp said bit in said bit carrying portion, said shield extending around the sides and forward and rear ends of said bit carrying portion, and means connected between said bit carrying portion and the rear end of said shield for engaging said shield with a cutter bit in said bit receiving recess and for holding said bit in said bit carrying portion.

3. In a cutter chain, a plurality of alternately arranged bit carrying and connecting links, each of said bit carrying links having a projecting bit carrying portion having a bit receiving recess formed therein, and means for protecting said bit receiving portion against abrasion and for holding a cutter bit in said bit carrying portion including a shield adapted to enclose the advance end and sides of said bit carrying portion and mounted for longitudinal slidable movement with respect thereto, said shield having an inner face adapted to engage a forward face of a cutter bit and means for positively engaging said shield with said cutter bit for holding said bit in said bit receiving recess, and an interengaging tongue and slot connection between said bit carrying portion and the inside of the advance end of said shield, arranged to prevent outward movement of said shield with respect to said bit carrying portion but to permit longitudinal movement of said shield with respect to said bit carrying portion, when said means for engaging said shield with said cutter bit is released, to permit removal of said shield from said bit carrying portion.

4. In a cutter chain, a plurality of alternately arranged bit carrying and connecting links, each of said bit carrying links having a projecting bit carrying portion having a bit receiving recess formed therein, and means for protecting said bit carrying portion against abrasion and for holding a cutter bit therein including a shield adapted to enclose the advance end and sides of said bit carrying portion and mounted for longitudinal slidable movement with respect thereto, said shield having an inner face adapted to engage a forward face of a cutter bit, for holding said bit to said bit receiving recess, a tongue projecting forwardly from said bit carrying portion adjacent the lower end thereof, a slot formed on the inside of said shield and adapted to be engaged by said tongue, said tongue and slot being so arranged as to prevent outward displacement of said shield with respect

to said bit carrying portion, but arranged to permit complete removal of said shield from said bit carrying portion when desired.

5. In a cutter chain, a plurality of alternately arranged bit carrying and connecting links, each of said bit carrying links having a projecting bit carrying portion having a bit receiving recess formed therein, and means for protecting said bit carrying portion against abrasion and for holding a cutter bit in said bit carrying portion including a shield adapted to enclose the advance end and sides of said bit carrying portion and mounted for longitudinal slidable movement with respect thereto, said shield having an inner face adapted to engage a forward face of a cutter bit for holding said bit in said bit receiving recess, and a tongue and slot connection between said bit carrying portion and the inside of said shield, arranged to prevent outward movement of said shield with respect to said bit carrying portion but to permit removal of said shield from said bit carrying portion, and means having connection with the rear face of said bit carrying portion and with said shield, for drawing said shield towards the cutter bit and for causing said shield to hold said bit in engagement with said bit carrying portion.

6. In a cutter chain, a plurality of alternately arranged bit carrying and connecting links, each of said bit carrying links having a projecting bit carrying portion having a bit receiving recess formed therein, and means for protecting said bit carrying portion against abrasion and for holding a cutter bit therein including a shield adapted to enclose the advance end and sides of said bit carrying portion and mounted for longitudinal slidable movement with respect thereto, said shield having an inner face adapted to engage a forward face of a cutter bit for holding said bit in said bit receiving recess, a tongue and slot connection between said bit carrying portion and the inside of said shield, arranged to prevent outward movement of said shield with respect to said bit carrying portion, but to permit removal of said shield from said bit carrying portion, and a screw threaded within the rear face of said shield and having interengaging bearing connection with the rear portion of said bit carrying portion, for drawing said shield longitudinally towards the cutter bit and for holding said shield in engagement with said cutter bit.

25 EDWARD J. DOBERSTEIN.
